VACUUM PUMP

Filed Feb. 5, 1927

Inventor

Howell V. Ringgenberg

By Clarence O'Brien
Attorney

UNITED STATES PATENT OFFICE.

HOWELL V. RINGGENBERG, OF ROCHESTER, MINNESOTA, ASSIGNOR OF ONE-HALF TO
ROY E. OESTERREICH, OF ROCHESTER, MINNESOTA.

VACUUM PUMP.

Application filed February 5, 1927. Serial No. 166,210.

This invention relates to new and useful improvements in vacuum pumps and has for its primary object to provide a pump of this character that is extremely simple of 5 construction, inexpensive of manufacture and installation, and one that may be used in the pumping of oil, water, or other fluid.

With the foregoing and other objects in 10 view as the nature of the invention will be better understood, the same comprises the novel form, combination and arrangement of parts hereinafter more fully described, shown in the accompanying drawing and claimed.

15 In the drawing wherein like reference characters indicate corresponding parts.

The figure is a vertical section through a vacuum pump constructed in accordance with the present invention.

20 Now having particular reference to the drawing, 5 designates a cylindrical body open at its upper and lower ends and externally screw threaded at said ends as disclosed in the drawing. Threaded upon the 25 upper end of this body 5 is a flanged lid 6, while threaded upon the lower open end of said body is a circular chamber 7 formed internally adjacent its upper end with a circumferential flange 9 for the purpose of securing a flexible circular diaphragm 10 between the body 5 and said chamber 7. Arranged through the center of the diaphragm 10 in an air tight manner is a vertical rod 11, the upper end of which projects into the 30 relatively large bore 12 of a circular nipple 13 upon the upper end of which is arranged a cap 14 having air openings 15 in the top wall thereof. For the purpose of at times closing the bore 12 of the nipple 13 35 to the atmosphere, there is provided a ball valve 16 while arranged between this ball and the upper end of the rod 11 is a small 40 expansible coil spring 17 for a purpose hereinafter more fully described.

45 Surrounding the rod 11 between the nipple 13 and said diaphragm 10 is an expansible coil spring 18, while formed or disposed within the chamber 7 at opposed 50 points are conventional inlet and exhaust check valves 19 and 20, respectively, that have communication with a fluid intake 21 and discharge pipe 22.

55 Leading into the body 5 is a vacuum pipe line 23 and in operation when a vacuum is created in the body 5 above the diaphragm

10 the ball 16 will tightly close the bore 12 of the nipple 13 and at the same time the diaphragm 10 will be raised. During the raising of the diaphragm, the rod 11 will move upwardly for compressing the spring 60 17 between the rod and said ball and when said spring is compressed to a certain degree, the ball will be caused to rise from the nipple breaking the vacuum. During the raising of the diaphragm the fluid will 65 be drawn into the chamber 7 through the valve 19. As soon as the vacuum becomes broken the spring 18 will cause the return action of the diaphragm 10 until the ball 16 closes the passage through the nipple 13, at 70 which time the action repeats itself. During the return of the diaphragm the fluid is obviously ejected through the exhaust check valve 20 and exhaust pipe 22.

75 It will thus be seen that I have provided a highly novel, simple, and efficient vacuum pump that is well adapted for all the purposes heretofore designated, even though I have herein shown and described the invention as consisting of certain detail structural elements it is nevertheless to be understood 80 that some changes may be made therein without affecting the spirit and scope of the appended claims.

Having thus described the invention, what I claim is:

1. In a pump of the class described, a hollow closed body, a diaphragm arranged within the body for dividing the same into upper and lower compartments, a vacuum pipe communicating with the upper compartment, an inlet and exhaust valve arranged in the lower compartment and communicating respectively with a fluid supply and a fluid storage, a normally closed air inlet valve associated with the upper compartment, automatic means for opening the air inlet valve when the diaphragm has been raised to a predetermined degree for breaking the vacuum within the upper compartment, and means for returning the diaphragm when the vacuum is broken for allowing said valve to close whereby the vacuum is again created in the upper compartment, and simultaneously forcing the fluid in the lower compartment outwardly through the exhaust valve.

2. In a pump of the class described, a hollow body open at its upper and lower ends, a lid for the upper open end of the

body, a chamber detachably secured on the open lower end of the body, a diaphragm secured between the open lower end of the body and said chamber whereby to form a partition between the body and the chamber, and a vacuum compartment in the hollow body, a vacuum pipe communicating with the vacuum compartment, inlet and exhaust valves arranged in the chamber and communicating respectively with the fluid supply and fluid storage, a normally closed air inlet valve for the vacuum compartment arranged in said lid, automatic means for opening the air inlet valve when the diaphragm has been raised to a predetermined degree for breaking the vacuum in the vacuum compartment, and means for returning the diaphragm when the vacuum is broken for allowing said air inlet valve to close whereby the vacuum is again created in said compartment, and simultaneously forcing the fluid in the chamber outwardly through the exhaust valve.

3. In a pump of the class described, a hollow body open at its upper and lower ends, a lid for the upper open end of the body, a chamber detachably secured on the open lower end of the body, a diaphragm secured between the open lower end of the body and said chamber whereby to form a

partition between the body and the chamber, and a vacuum compartment in the hollow body, a vacuum pipe communicating with the vacuum compartment, inlet and exhaust valves arranged in the chamber and communicating respectively with the fluid supply and fluid storage, a nipple carried by the lid and communicating with the vacuum compartment, a ball valve normally seated on the nipple for closing the bore thereof to prevent the admission of air to the vacuum compartment, a rod extending vertically in the hollow body and the chamber and carried by the diaphragm for movement therewith, cooperating means between the upper end of the rod and said ball valve for opening the air inlet valve when the diaphragm has been arranged to a predetermined degree for breaking the vacuum within the vacuum compartment, and an expandable coil spring for returning the diaphragm and rod to their initial positions when the vacuum is broken to allow the air inlet valve to close to again create the vacuum in the vacuum compartment, and simultaneously forcing the fluid in the chamber outwardly through the exhaust valve.

In testimony whereof I affix my signature.

HOWELL V. RINGGENBERG.
